UNITED STATES PATENT OFFICE.

ARNATT READING GULICK, OF BROOKLYN, NEW YORK.

DESIGN FOR A BED-PAN.

SPECIFICATION forming part of Design No. 22,967, dated December 12, 1893.

Application filed November 17, 1893. Serial No. 491,275. Term of patent 14 years.

To all whom it may concern:

Be it known that I, ARNATT READING GULICK, a citizen of the United States, residing at Brooklyn, in the county of Kings and State of New York, have invented a new and useful Design for Bed-Pans, of which the following is a specification.

Figure 1 is a perspective view of my new design, and Fig. 2 is a sectional view of the same.

10 The leading feature of my design consists in a pan of substantially the shape shown, in which the body A has parallel sides *a*, *a*, one end *B* being rounded or curved while the other end *C* has curved corners *c*, *c*. The sides are 15 inclined from near their longitudinal centers toward the end *C* and this portion of the pan

has a cover *D* which is curved in cross section. Around the opening *E* is a beaded edge *e* which slopes and merges into the cover *D*. On the end *B* is a downwardly curved lip projection *F*. 20

What I claim is—

The design for a bed pan, substantially as shown and described.

In testimony whereof I have signed my 25 name to this specification in the presence of two subscribing witnesses.

ARNATT READING GULICK.
